UNITED STATES PATENT OFFICE

163,614

SANDAL

Clayton A. Laughlin, Minneapolis, Minn.

Application July 19, 1950, Serial No. 11,257

Term of patent 14 years

(Cl. D7—7)

To all whom it may concern:

Be it known that I, Clayton A. Laughlin, a citizen of the United States, residing at Minneapolis, Hennepin County, Minnesota, have invented a new, original, and ornamental Design for Sandal, of which the following is a specification, reference being had to the accompanying drawing, forming a part hereof.

Fig. 1 is a front perspective view of a sandal, showing my new design;

Fig. 2 is a top plan view thereof, the lacing shown in Fig. 1 being omitted from Figs. 2, 3 and 4 for convenience of illustration;

Fig. 3 is a front elevational view; and

Fig. 4 is a side elevational view of the opposite side shown in Fig. 1.

The shoes will be made in pairs, each pair consisting of a shoe for the left foot and a shoe for the right foot, the shoe for the right foot corresponding to the shoe for the left foot illustrated except for slight differences in contour.

I claim

The ornamental design for a sandal, substantially as shown and described.

CLAYTON A. LAUGHLIN.
